UNITED STATES PATENT OFFICE.

ALEXANDER J. LOGA, OF ALLIANCE, OHIO.

SLICING-MACHINE.

1,115,697.

Specification of Letters Patent. Patented Nov. 3, 1914.

Application filed November 24, 1913. Serial No. 802,811.

To all whom it may concern:

Be it known that I, ALEXANDER J. LOGA, citizen of the United States, residing at Alliance, in the county of Stark and State 5 of Ohio, have invented certain new and useful Improvements in Slicing-Machines, of which the following is a specification, reference being had to the accompanying drawings.

10 This invention relates to improvements in cabbage cutting machines and has for its primary object to provide a machine of this character primarily designed for use in the manufacture of sauer kraut, whereby large 15 quantities of cabbage may be expeditiously cut into particles of a predetermined thickness.

15 The invention has for another and more particular object to provide a machine of the above character embodying a movable knife and a gage plate movable therewith, and means for adjusting the gage plate with respect to the knife whereby the thickness of the slices cut from the cabbage head may be 20 varied as desired.

25 In its more specific aspect, the invention includes a hopper having an inclined feed chamber, a knife vertically movable at the lower end of the feed chamber, stationary 30 guides for the knife, a gage plate, link connections between one end of said gage plate and the knife, movable guides for the gage plate, and means for moving said guides to adjustably dispose the gage plate in spaced 35 relation to the knife.

35 The invention has for a further object to generally improve and simplify the construction of machines of the above character without increasing their manufacturing cost 40 to any material extent.

With the above and other objects in view as will become apparent as the description 45 proceeds, the invention consists in certain constructions, combinations and arrangements of the parts that I shall hereinafter fully describe and claim.

50 For a full understanding of the invention, reference is to be had to the following description and accompanying drawings, in which—

55 Figure 1 is a side elevation of a cabbage cutting machine embodying my invention in its preferred form; Fig. 2 is a top plan view thereof; Fig. 3 is an end elevation; Fig. 4 is a similar view of the opposite end of the machine; Fig. 5 is a section taken on the

line 5—5 of Fig. 2; Fig. 6 is a section taken on the line 6—6 of Fig. 5; Fig. 7 is a detail elevation of the cutting knife; Fig. 8 is a detail perspective view of one of the guide 60 members for the gage plate.

Referring in detail to the drawings, 5 designates a casing or housing which is provided with a longitudinally inclined hopper or feed chamber 6. The base wall of this 65 hopper at its lower end has the metal plate 7 counter-sunk in its upper surface for a purpose which will become apparent as the construction of the invention is better understood.

70 In the opposed faces of the side walls of the casing 5 at the lower end of the feed chamber, the steel plates 8 are secured, said plates being counter-sunk in the casing walls. Similar plates 9 are also secured to 75 the outer faces of the side walls of the casing. These plates are provided adjacent their upper and lower ends with the curved slots 10 which coincide with similar slots formed in the side walls of the casing. The 80 longitudinal edges of the plates 8 which are contiguous to the lower end of the hopper chamber 6 are provided with guideways 11 to receive the edges of a cutting plate 12. The lower body portion of this plate is cut 85 out to form the opening 13 therein, and the upper end of said opening is curved and sharpened to provide the cutting edge 14. The top wall of the casing 5 is provided with a transverse slot 15 through which the cutting plate is adapted to extend in the operation 90 of the machine. A transversely disposed bar 16 is secured to one side of said plate at its upper end and rods 17 connect the opposite ends of said bar to the levers 18 95 which are fulcrumed as at 19 upon the ends of a rod 20 which is mounted in and connects the opposed side walls of the casing 5.

21 designates the gage plate which is movable with the cutting plate 12 and is mounted 100 at its edges in the guide members 22. Each of these guide members is formed upon the end of a bolt 23 which is adapted for disposal through a sleeve 24 formed upon one end of a lever 25. These sleeves are adapted 105 for movement in the slots 10 and the corresponding openings in the casing walls. Suitable nuts 26 are threaded upon the outer ends of the bolts to retain the same in the sleeves 24. The levers 25 are fixed upon the 110 ends of the transverse rods 27 which extend through the plates 8 and 9 and are loosely

mounted in the side walls of the casing. The levers 25 on one side of the casing 5 are provided with arms 28 to which the ends of a link 29 are pivotally connected. The 5 arm 28 of the upper lever is somewhat longer than the arm of the lower lever and a nut 30 is loosely mounted in the end of said longer arm. To this nut, the lower end of an adjusting screw 31 is rotatably connected. This screw is threaded in a sleeve 32 secured upon a bracket 33 mounted upon the casing 5, the upper end of said screw being provided with a suitable crank handle 34 whereby the screw may be turned. 10 Upon opposite ends of the bar 35 secured to the side wall of the casing 5, the stop pins 36 are mounted. These pins limit the movement of the levers 25.

The gage plate 21 is provided with a crescent shaped opening 37, and the cutting edge of the plate 12 is disposed slightly above the lower edge of this opening. The upper edge of the gage plate 21 is connected to the bar 16 which is secured upon the cutting 25 plate 12 by means of the links 38.

It will be apparent from the above description that by simply turning the adjusting screw 31, the levers 25 are actuated to move the guide members 22 in the curved slots 30 provided in the side walls of the casing, and thus move the gage plate toward or from the cutting plate as the case may be. It is, of course, understood that the stems 23 of the guide members are loosely engaged in the 35 sleeves 24 so that they will rotate freely therein. The distance between these plates determines the thickness of the slice of cabbage cut from the head. In order that this distance may be accurately determined, I 40 provide upon the lever 25 having the longer arm 28, a suitable indicating pointer 39 which moves over the scale graduations 40 cut upon the surface of one of the plates 9.

In order to forcibly feed the cabbage to 45 the cutting plate 12, I provide a follower 41 arranged within the hopper or feed chamber 6. One end of a rack bar 42 is secured to this follower and the teeth 43 of said rack bar are adapted to engage the 50 teeth of a pinion 44 disposed between the bracket plates 45 fixed upon the end wall of the hopper 6 in which one end of a shaft 46 is journaled. The bar 42 is movable through a suitable opening provided in the 55 end wall of the hopper and has a hand loop 47 formed upon one end. A pin 48 is also secured to the outer end of said bar and engages the bracket plates 45 to limit the movement of the follower in one direction. 60 To the other end of the shaft 46, one end of a helical spring 49 is secured, said spring being arranged between the spaced plates 50 and having its other end secured to one of the connecting bolts between said plates. 65 This spring, normally acts to rotate the

pinion 44 so as to move the follower inwardly and downwardly toward the cutting plate 12. It will be readily understood that in the operation of the machine, the cabbage is disposed between the follower 70 and the cutting plate 12, and the spring 49 acts to continually press the cabbage head against the cutting plate until the entire head has been cut.

The rear ends of the levers 18 are connected to the opposite ends of a transverse shaft 51 which is mounted for movement in the arcuate slots 52 provided in the side walls of the case 5. Upon this shaft between the side walls of the casing, the arms 80 of a yoke 53 are loosely mounted. Upon a shaft 54, journaled in the side walls of the casing, a fly wheel 55 is secured and on said shaft, an eccentric 56 is rigidly fixed. Upon the periphery of this eccentric 85 the strap 57 is arranged and a rod 58 connects said eccentric strap with the yoke 53. A pinion 59 is also secured upon the shaft 54 for engagement with the teeth of a gear wheel 60, secured upon the operating shaft 90 61 which is journaled in the side walls of the casing 5. Upon one end of this shaft, a belt wheel 62 is secured with which the belt extending from an engine or other suitable source of power is engaged.

From the foregoing description taken in connection with the accompanying drawings, it is believed that the construction and manner of operation and several advantages of the invention will be clearly and fully understood.

When power is applied to the shaft 61, the levers 18 are oscillated to actuate the cutting plate through the medium of the connecting rods 17. In the vertical movement of this plate, it is apparent that the gage plate 21 which is connected thereto is also moved in the casing, but during such movement its position with respect to the cutting plate is not altered. When the crescent shaped opening 37 in the plate 21 and the cutting edge of the plate 12 are disposed above the base of the hopper or feed chamber 6, the follower 41 forces the cabbage head through the opening in the cutter plate. In the reverse or downward movement of the plates 12 and 21, the knife edge 14 of the cutter plate coöperating with the metal plates 7 on the base wall of the feed chamber severs the layer of cabbage from the head. This cabbage layer is forced outwardly through the opening 37 in the gage plate 21. It is apparent that the thickness of the severed layer of cabbage is determined solely by the space between the movable plates. In this manner, it will be appreciated that a large number of cabbage heads may be easily, expeditiously and economically cut up into minute particles for use in manufacturing sauer kraut.

The machine is comparatively simple in its construction and it will therefore be appreciated that the same can be manufactured at small cost.

5 It will of course be understood that the invention is susceptible of considerable modification in the form, proportions and arrangements of the several elements employed and I therefore reserve the right to 10 resort to all such legitimate changes as may be fairly embodied within the spirit and scope of the invention, as claimed.

Having thus described the invention, what is claimed is:

15 1. In a machine of the character described, a movable cutter plate, a gage plate disposed in parallel relation to the cutter plate, movable connections between one end of the gage plate and said cutter plate, 20 and means for moving said gage plate toward or from the cutter plate.

2. In a machine of the character described, a vertically movable cutter plate, a gage plate connected to the cutter plate and 25 movable therewith, guides for said gage plate, and means for adjusting said guides to move the gage plate toward or from the cutter plate.

3. In a machine of the character described, a vertically movable cutter plate, a gage plate, links connecting one end of the gage plate to the cutter plate, movable guide members for said gage plate, and means for moving the guides to dispose the gage plate 35 in adjustable spaced relation to the cutter plate.

4. In a machine of the class described, a vertically movable cutter plate, stationary guides therefor, a gage plate, movable 40 connections between one end of the gage plate and the cutter plate, normally stationary adjustable guides for the gage plate to maintain said plate in spaced parallel relation to the cutter plate, and means for adjusting said guides to vary the distance between said plates.

5. In a machine of the class described, a vertically movable cutter plate, stationary guides therefor, a gage plate, links movably connecting one end of said gage plate to the cutter plate, normally stationary adjustable guide members for said gage plate, pivotally mounted arms connected to said guide members, and means for actuating 55 said arms to adjust the guide members and move the gage plate toward or from the cutter plate.

6. In a machine of the class described, the combination with a casing provided 60 with a hopper, of a vertically movable cutter plate, mounted in said casing at one end of the hopper, stationary guides for said cutter plate, a gage plate, movable connec-

tions between one end of the gage plate and the cutter plate, transverse rods loosely 65 mounted in the side walls of the hopper, levers secured upon the ends of each rod, the side walls of the casing being provided with slots, guide members for the gage plate connected to said levers and movable in 70 said slots, a link connecting the levers on one side of the casing, an adjusting screw connected to one of said levers whereby said rods are rotated and the arms simultaneously moved to adjustably position the 75 guide members in the slots and vary the distance between the cutter plate and the gage plate.

7. In a machine of the character described, a movable cutter plate, a gage plate 80 arranged in parallel relation to the cutter plate and connected to said cutter plate at one of its ends for movement therewith, a plurality of guide members in which the opposite edges of the gage plate are movably 85 disposed, and means for simultaneously moving said guide members to adjust the gage plate with respect to the cutter plate and vary the distance between said plates.

8. In a machine of the character described, a movable cutter plate, a gage plate, links connecting one end of the gage plate with said cutter plate, a guide for the gage plate, and means for adjusting said guide to move the gage plate toward or from the 95 cutter plate and vary the distance between said plates.

9. In a machine of the character described, a movable cutter plate, a gage plate, movable connections between one end of the 100 gage plate and the cutter plate, a loosely mounted transverse rod, arms fixed upon the ends of said rod, a guide member loosely mounted upon each of said arms to receive one edge of the gage plate, and means for 105 rotating said rod to move the guide members and adjust the gage plate with respect to the cutter plate.

10. In a machine of the character described, a movable cutter plate, a gage plate 110 disposed in parallel relation to the cutter plate and connected at one of its ends thereto for movement with the cutter plate and also independently thereof, movable guide members in which the opposite edges 115 of the gage plate are disposed, and means for simultaneously moving said guide members to move the gage plate toward or from the cutter plate and vary the distance between the same.

In testimony whereof I hereunto affix my signature in the presence of two witnesses.

ALEXANDER J. LOGA.
